AUTOMATIC CLOCK CALENDAR

Loren E. Wolfgang, Fortville, Ind.

Application January 7, 1953, Serial No. 329,972

13 Claims. (Cl. 40—114)

The present invention relates to calendars and particularly to a motor driven, automatic type calendar.

The primary object of the invention is to provide such a calendar having three drums mounted for rotation upon a common shaft, one of said drums bearing the numerals 1 to 31, another of said drums bearing the names of the days of the week, and the third drum bearing the names of the months of the year, said calendar further having means for turning the day and date indicating drums at the end of each day, and means for turning the month indicating drum at the end of each month.

A further object is to provide means whereby the calendar will automatically adjust itself to compensate for the extra day during the "leap" years.

Ancillary objects will become apparent as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a rear elevational view of calendar mechanism embodying my invention;

Fig. 2 is a fragmentary elevation of a preferred form of drive means for the calendar mechanism illustrated in Fig. 1;

Fig. 3 is a fragmentary elevational view similar to Fig. 1 but showing the drum actuating mechanism in another position in the operating cycle;

Fig. 4 is a further elevational view similar to Fig. 3 but showing the drum actuating mechanism in still another position;

Fig. 5 is an end elevation of the date indicating drum taken substantially on line 5—5 of Fig. 1;

Fig. 6 is an end elevation of the month indicating drum taken substantially on line 6—6 of Fig. 1;

Fig. 7 is an end elevation of the day indicating drum taken substantially on the line 7—7 of Fig. 1;

Fig. 8 is a fragmentary sectional view taken substantially on line 8—8 of Fig. 7 and showing a detail of the drive mechanism for the day indicating drum;

Fig. 9 is a fragmentary sectional view of an element of the calendar mechanism taken substantially on line 9—9 of Fig. 6 but at a time when the element is in its lowermost position; and

Fig. 10 is a perspective view of an element of the calendar actuating mechanism.

Referring more particularly to the drawings, a shaft 10, supported at opposite ends in suitable brackets 11 and 12, has journaled thereon in axially spaced relation, three drums 13, 14 and 15. For purposes of this specification, I prefer to call drum 13 the "date drum," drum 14 the "month drum," and drum 15 the "day drum."

About its periphery, date drum 13 has the numerals 1 to 31 inscribed thereon at equally spaced intervals; about its periphery, month drum 14 has the names of the months

2

of the year inscribed thereon at equally spaced intervals; and, about its periphery, day drum 15 has the names of the days of the week inscribed thereon at equally spaced intervals. I have found it more expedient to provide the day drum 15 with two sets of week day names, so that there are fourteen such names on that drum as compared to twelve names on the month drum. This is done so that the angular stepping of the drum 15 need not vary too unduly from the angular stepping of the drum 13.

In the front wall of housing H in which the calendar is enclosed, there are three apertures. Aperture 16 registers with date drum 13, aperture 17 registers with month drum 14, and aperture 18 registers with day drum 15, so that only one day name, one month name and one date will appear, through said apertures or windows on the face of the calendar, as, for instance, "Wednesday January 25."

Because of the number of numerals on date drum 13, that drum must be turned, at the end of each day, through one-thirty-first of a revolution. The day drum 15, however, must be turned through one-fourteenth of a revolution each day, and the month drum 14 must be turned through one-twelfth of a revolution at the end of each month. It is the mechanism for accomplishing this movement of the drums with which my invention is primarily concerned.

The drive or actuating mechanism for the drums comprises a push-rod 19 having one end mounted and guided upon, for instance, a headed stud 20 fixed to the housing H and passing through an axially-extending slot 21 in rod 19. Preferably, a cam 22 engages the end of rod 19 and is driven by a conventional clock motor, or the like (not shown) to make one revolution in each twenty-four hours. The cam is so shaped that, through substantially 360° of the revolution thereof, rod 19 is moved steadily downward as viewed in Fig. 1. As the cam completes a revolution, as, for instance, at midnight each night, its highest point 23 releases the rod 19 which thereupon moves rapidly upward under the influence of a spring 24, or the like.

A crank arm 25 is fixed to shaft 10, projecting radially therefrom, and is pivotally connected to the lower end of push-rod 19. As the rod 19 is axially reciprocated by the cam and spring arrangement, shaft 10 will be oscillated in brackets 11 and 12.

One end wall 26 of date drum 13, carries a series of peripherally spaced indexing means indicated generally by the reference numeral 27. For the purpose of this invention, there are thirty-one such means, equiangularly spaced about a common circle concentric with shaft 10. Twenty-seven of such means preferably constitute radial slots 28 through the end wall 26. The remaining consecutive four of such means constitute tabs (the group of tabs being indicated generally by the numeral 29) raised out of the plane of drum end 26. Tab 29a is raised only a short distance out of the plane of end 26, tab 29b is raised slightly farther out of the said plane, tab 29c is raised still farther out of that plane, and tab 29d is raised still farther out of said plane. In other words, the tabs are raised progressively farther out of the plane of the wall in which are formed the slots 28, counting in the direction opposite the direction of rotation of drum 13.

The end wall 30 of month drum 14, facing end wall 26 of date drum 13, likewise carries a series of indexing means, indicated generally by the reference numeral 31. For the purpose of this invention, there are twelve such means, one for each month of the year, equiangularly spaced about a common circle concentric with shaft 10 and preferably radially spaced from such shaft a distance substantially equal to the radial spacing of means 27 on drum 13. Those indexing means which correspond to those months having thirty-one days preferably constitute radial slots 32 through the end wall 30.

similar to slots 28 in drum 13. Those indexing means which correspond to the months of the year having thirty days preferably constitute tabs 33 raised out of the plane of end wall 30 to lie in a common plane. The indexing means which corresponds to the month of February comprises a generally planar element 34 mounted for rotation upon a pivot or trunnion 35 substantially perpendicular to a radius of drum 14. Said element 34 has four radially projecting fingers, each carrying a toe turned out of the plane of said element in the direction opposite that of the drum rotation. The trunnion 35 is so positioned, relative to an opening 32' in the drum end wall 30 that the fingers 36 and 37 will project successively through said aperture as the element 34 is turned about the axis of said trunnion. The direction of projection of said fingers, of course, is the direction in which the tabs 33 are raised out of the plane of the wall 30. Finger 36 is slightly shorter than the remaining three fingers 37 of said element, and is of such length that, when the element 34 is so disposed that finger 36 projects through said aperture 32', its toe will lie slightly beyond the plane common to the free ends of tabs 33. The remaining three fingers 37 are of such length as to locate their toes still farther beyond said common plane, when positioned to project through said aperture. Obviously, only one of said fingers can lie in such projected position at any one time.

A stationary cam 38 is fixed closely adjacent drum 14 and in the path of the fingers of element 34. Each time element 34 is moved past cam 38, the currently projecting finger will engage the cam and element 34 will be rotated through 90°, retracting that finger and placing the next finger in such projected position. This structure is for the purpose of automatically compensating for the added day in February during the "leap" year and its operation will presently become apparent.

To provide a driving connection between shaft 10 and the indexing means on drums 13 and 14, I provide a supporting member or arm 39 (see detail Fig. 10) fixed to shaft 10 for rotation therewith by means of a pin 40 passing diametrically through the shaft and oscillably mounting member 39 for limited oscillation about the axis of such pin.

A pawl 41 is carried on the other end of arm 39, and, in the illustrated embodiment of my invention, comprises a triangular shaped portion of arm 39 turned out of the plane of said arm, substantially at right angles thereto, toward the end 26 of drum 13. Pawl 41 is radially spaced from shaft 10 a distance substantially equal to the radial spacing of the indexing series 27. Resilient means such as spring 42 urges the free end of member 39 toward drum end 26 thus urging pawl 41 into operative engagement with the indexing series 27. As shown, one end of spring 42 is anchored on arm 39, while the other end thereof bears against shaft 10.

As shaft 10 is oscillated by push-rod 19, member 39 is likewise oscillated causing pawl 41 to engage certain ones of the indexing means of series 27.

Since there are only twelve positions for drum 14, in order that said drum will be turned through one-twelfth revolution, arm 39 must be angularly oscillated through at least 30°. But since drum 13 must occupy 31 positions, it must be turned through only one-thirty-first of a revolution upon each oscillation of member 39. Obviously, therefore, some type of lost motion means must be provided so that pawl 41 will be held out of operative engagement with the indexing means of series 27 until only about 11° 30' of the 30° movement of member 39 remains.

To this end, I provide a cam 43 comprising a body portion 44 pivoted as at 44' to a bracket 45 for oscillation in a plane substantially parallel to the axis of shaft 10 but radially spaced therefrom. Body portion 44 supports a pair of substantially parallel arms 46 and 47 projecting away from the pivot 44' and curved to con-

form substantially to a circle concentric with shaft 10 on a radius slightly greater than the distance of pawl 41 from said shaft.

Arm 46 has an end portion 48 turned out of the line of the arm toward drum end 26, preferably at an angle of approximately 45° with said arm. Arm 47 has a similar end portion 49 similarly turned from the line of arm 47 toward drum end 26, for a purpose later to become apparent.

The end of arm portion 48 is notched as at 50 to define a finger 51 projecting beyond the end of said portion. A spring 52 engages the portion 44 to rock cam 43 about pivot 44' toward drum 13. When one of those means of the indexing series 27 corresponding to the numerals 1 to 27, is in registry with arm portion 48, finger 51 will take into one of the slots 28 in the drum end 26. When, however, one of those four means 29, corresponding to the numerals 28, 29, 30 and 31, is in registry with cam portion 48, the end of one of these tab means will take into the notch 50 in said portion. In either event, it will be seen that the end portion 48 will thus hold the current date numeral in proper registry with aperture 16.

Member 39 has a portion, here constituting a pin 52, projecting radially beyond pawl 41, and interengaging the adjacent edges of the arms 46 and 47. Thus, as the arm 39 swings about the axis of shaft 10 in response to reciprocation of the push-rod 19, the pin 52 is guided, by the currently-engaged portions of the cam 43, to cause the arm 39 to swing about the axis of pin 40 to assume positions dependent upon the current positions of the cam 43 and the push-rod 19, in a manner to be explained hereinafter.

Member 39 is further provided with a hook 54 for operative engagement, at times, with the indexing means 31 on drum 14. In the illustrated embodiment of my invention, hook 54 is formed in a plate 55 oscillably journaled on pin 53 and is formed with an arcuate slot 56 therein centered on pin 53. A second pin 56', carried by member 39, takes into the slot to limit the oscillation of the plate about pin 53. Such oscillation will, as seen in Fig. 10, move hook 54 toward and away from pawl 41. A spring 57, carried on member 39 and engaging plate 55, urges hook 54 toward its position farthest from pawl 41.

Drum 13 is provided with a counterweight 58, so positioned as to bias drum 13 toward a position in which the numeral 1 will appear in window 16. Since the momentum of drum 13, under the influence of counterweight 58, and when released by the mechanism above described, would carry the drum past that point, I provide an abutment member 59 comprising a pin projecting from the end 26 of drum 13. Cam 43 further is provided with a finger 60 near pivot 44' projecting into the path of pin 59. Such finger is moved into the path of pin 59 only when cam 43 is rocked toward drum 14 in a manner to be described hereinafter. Pin 59 strikes finger 60 to arrest rotation of the drum with the numeral 1 in registry with window 16.

In order that drum 14 will remain fixed in the position to which it is rotated each time by hook 54, I provide braking means comprising a brake shoe 9 (Fig. 1) resiliently held in restraining engagement with drum 14.

Day drum 15 has a series of peripherally spaced indexing means 61 arranged in a circle concentric with shaft 10 on end 62 thereof and constituting, preferably, a plurality of equiangularly spaced radial slots, one for each day of the week. As heretofore stated, I prefer to provide two sets of day names and a corresponding number of slots 61 so that the drum may be moved through one-fourteenth, rather than one-seventh, of a revolution upon each reciprocation of the push-rod 19.

A ratchet dog 63 is fixed to shaft 10 upon a resilient arm 64 and is adapted to engage successively in slots 61. As shaft 10 is oscillated by push-rod 19, arm 64 will

swing dog 63 angularly about the shaft axis. The dog is triangularly shaped, as shown in Fig. 8, and when moved in the direction opposite to that of drum rotation, edge 65 thereof rides up out of the slot 61. Moving in the opposite direction, the square edge 66 engages in one of slots 61 thereby rotating drum 15 to place the name of the next day in registry with window 18. Brake means similar to that for drum 14 is provided and comprises a brake shoe 67 resiliently held in restraining engagement with drum 15 whereby said drum is held against movement except by dog 63.

Assuming that the month is November, the date is the 26th and the day is Wednesday, the numeral "26" on the drum 13 will be displayed through window 16, the name "November" on the drum 14 will be displayed through the window 17 and the name "Wednesday" on the drum 15 will be displayed through the window 18. The cam 43 will be in its extreme counter-clockwise position, under the influence of the spring 52, so that the finger 51 thereof will be engaged in one of the slots 28. If it is approximately noon, the cam 22 will be in its illustrated position as shown in Fig. 2 and the arm 39 will be in a position, relative to the horizontal, somewhat lower than that illustrated in Fig. 1, so that the pin 53 will be approximately at the break in the upper surface of the finger 43. Thus, the pawl 41 will be out of engagement with any of the indexing means 27 or 29.

As the cam 22 continues to rotate, the shaft 10 will be oscillated in a clockwise direction as viewed from the left of Fig. 1, the pin 53 will move more deeply into the slot between the portions 46 and 47 of the cam 43, and the toe 63 of the arm 64 will be riding the outer surface of the end wall of the drum 15, between slots 61.

When the high point 23 of the cam 22 is just about to pass the upper end of the push-rod 19, the toe 63 of the arm 64 will have dropped into one of the slots 61, the pin 53 will be at the bottom of the slot between the portions 46 and 47 of the cam 43, the pawl 41 will thus be out of engagement with any of the indexing means on the drum 13; and, since the finger 48 is resting against the end wall 26 of the drum 13, the cam 43 will be in such a position that the hook 54 will be spaced to the left (as viewed in Fig. 1) of any of the indexing means on the drum 14. Now, as the push-rod 19 drops off the high point 23 of the cam 22, the spring 24 will snap the push-rod to its uppermost position, thereby swinging the shaft 10 in a clockwise direction as viewed from the right of Fig. 1, to the limit of its stroke. As the pin 53 rides up relative to the cam 43, the spring 42 will hold that pin resiliently in contact with the right-hand surface of the portion 46-48 of the cam; and shortly after the pin passes the break in that surface, the pawl 41 will engage in one of the slots 28, to carry the drum 13 through one-thirty-first of a revolution, the parts being carefully proportioned and designed to hold the pawl out of engagement with the indexing means on the drum 13 through approximately 18° 30' of the 30° oscillatory stroke of the shaft 10. That slot in which the finger 51 has theretofore been engaged will cam against the under surface of that finger, as the drum moves, to shift the cam 43, against the tendency of the spring 52, to permit the drum to move and to permit the finger 51 to drop into the next slot 28. The drum 14 will be unaffected. The toe 63 of the arm 64, engaging in the next slot 61, with lost motion of approximately 4°, will shift the drum 15 through one-fourteenth of a revolution.

Now, the numeral "27" is displayed through the window 16, the name "Thursday" will be displayed through the window 18, and the name "November" will still be displayed through the window 17.

Upon the next reciprocation of the push-rod 19, the tab 29a will cam against the under surface of the finger 48, and the parts will come to rest with said tab 29a engaged in the notch 50. Now, the cam 43 will stand in a position somewhat closer to the adjacent end wall of

the drum 14, and the calendar will show "Friday, November 28."

The next reciprocation of the push-rod will result in lodging the tab 29b in the notch 50; and the next reciprocation will lodge tab 29c in the notch 50. Now, the calendar will show "Sunday, November 30"; and the cam 43 will be almost as far to the right as it is shown in Fig. 1.

Now, as the push-rod 19 moves downwardly again, the pin 53 will again ride the cam surface of the finger 48, whereby the radially outer end of the arm 39 will be shifted to the right, as viewed in Fig. 1, farther than on any reciprocation heretofore. As the pin 53 passes the break in that surface, the right-hand end of the plate 55 will strike the tab 33, corresponding to the month of November; and said plate will be swung about the axis of the pin 53 and against the tendency of the spring 57, to pass said tab. Of course, as soon as the plate has passed the tab, the plate will be swung again to the position illustrated in Fig. 10, by the action of the spring 57.

Now, as the high point 23 of the cam 22 leaves the push-rod, the hook 54, moving upwardly with the arm 39, will engage the said tab 33, whereby the arm 39 will be held against movement to the left along the surface of the finger 48 under the influence of the spring 42, and whereby the drum 14 will be turned through one-twelfth of a revolution. At the same time, the pawl 41 will be held out of engagement with the indexing means on the drum 13. As the arm 39 completes its upward movement, the pin 53 strikes the lower surface of the portion 49 of the cam 43 to shift the cam 43 momentarily into its ultimate clockwise position disengaging notch 50 from tab 29c whereby the counterweight 58 will be given an opportunity to turn the drum freely, and whereby the finger 60 is moved into position to engage the abutment member 59 to position the drum 13 with the numeral "1" in registry with window 16.

Now, the calendar will show "Monday, December 1." As arm 39 is once again started downward by cam 22, hook 54 will disengage from tab 33. When that happens, spring 42 will move arm 39 to the left, as viewed in Fig. 1, and into engagement with one of the slots 28. At the same time, spring 52 will rock cam 43 to the left and finger 51 into one of the slots 28.

Throughout the first twenty-seven days of December, the pawl 41 and cam finger 48 will cooperate with the indexing means 27 of the drum 13 in the manner first above described. On the 28th, the tab 29a will come to rest in the notch 50, on the 29th the tab 29b will come to rest in said notch, and on the 30th the tab 29c will come to rest in said notch. There is no tab 33 on the drum 14 corresponding to the month of December; but instead there is a notch or slot 32 corresponding to that month. Therefore, the hook 54 will remain inactive as the push-rod 19 is actuated at midnight on December 30; and the parts will be shifted to bring the tab 29d to rest in the notch 50. This, of course, brings the parts to the positions illustrated in Fig. 1; and when the push-rod is again reciprocated, the hook 54 will engage in the notch 32 corresponding to the month of December; and the drum 14 will be turned through 30° as the push-rod 19 moves upwardly, so that the calendar will show "Thursday, January 1."

1953 is not a leap year. Therefore, the element 34 will be positioned with one of its arms 37 projecting through the aperture 32'. It will be remembered that the arms 37 are longer than the arm 36 and that the arm 36 is so proportioned that, when it projects through the opening 32', its axial extent beyond the end of the drum is greater than that of the tabs 33. The element 34 is so proportioned and designed that, at the end of February of 1953, the currently-projecting arm 37 will be disposed in the path followed by the hook 54 when the tab 29a is seated in the notch 50—that is, at midnight

on February 28. Therefore, the hook 54 will engage the arm 37 of the element 34 as the push-rod 19 moves up on that occasion, the drum 14 will be turned, and the drum 13 will be temporarily released to permit the counterweight 58 to turn the drum 13 to a position in which the figure "1" will be displayed through the window 16.

Each time the element 34 passes the fixed cam 38, the element 34 will be turned through 90°. The intermediate arm 37 will thus project through the aperture 32' during 1954, and the third arm 37 will project through that aperture during 1955. Sometime prior to February of 1956, however, the element 34 will be turned to the position in which the arm 36 projects through the aperture 32'. Since the arm 36 is shorter than the arms 37, engagement of the tab 29a in the notch 50 will not move the cam 43 far enough to cause the hook 54 to engage the arm 36. Therefore, at midnight of February 28, 1956, the drum 13 will be moved and the drum 15 will be moved but the drum 14 will be unaffected; and the tab 29b will come to rest in the notch 50. The length of the tab 29b is such as to move the cam 43 sufficiently so that, upon the next reciprocation of the push-rod 19, the hook 54 will engage the arm 36, and the drum 14 will be moved together with the drums 13 and 15, the drum 13, of course, being released for movement under the influence of the counterweight 58, in that the calendar will show "Thursday, March 1."

Although the device herein described is relatively simple and inexpensive to manufacture, it embodies all the features necessary to make it a truly automatic calendar. So long as it is in continuous operation, driven by an accurate clock mechanism, it will indicate the correct date, month and day, automatically adjusting itself to compensate for "leap" years.

I claim as my invention:

1. For use with an automatic calendar of the type comprising a first drum, a second drum, and means mounting said drums in axially spaced relation for relative rotation about a common axis, the invention of actuating means for so rotating said drums, said first drum being provided with a first series of indexing means, and said second drum being provided with a second series of indexing means, said actuating means for said drums being located between said drums, and comprising a pawl, a hook, supporting means for said pawl and said hook supporting the same for generally axial movement between said first and second series of indexing means and for angular oscillation about the axis of said drums, driving means for so angularly oscillating said pawl and said hook once in each twenty-four hours, cam means operatively engageable by said supporting means to guide said pawl and said hook axially during such angular oscillation, said pawl being successively operatively engageable with the indexing means of said first series to rotate said first drum through a predetermined angle when said cam means is in one position, means incorporated in certain ones of said first series of indexing means and operatively engageable by said cam means to shift said cam means from a position near said first drum to a second position near said second drum, said supporting means being operatively engageable with said cam means when in said second position to shift said pawl, upon angular oscillation thereof, axially out of operative engagement with the indexing means of said first series and to shift said hook into operative engagement with certain ones of the indexing means of said second series to rotate said second drum through a predetermined angle, and brake means engaging said second drum to yieldably restrain rotation thereof.

2. The device of claim 1 in which said first drum is a date drum provided with a series of numerals from 1 to 31 spaced about the periphery thereof, said first series of indexing means being arranged angularly about one end thereof, one of such means for each such numeral, and in which said second drum is a month drum

provided with the names of the calendar months spaced about the periphery thereof, said second series of indexing means being arranged angularly about one end thereof, one of such means for each such name, said one ends of said drums being arranged in mutually facing relation.

3. The device of claim 2 in which said means mounting said drums comprises a shaft and said supporting means comprises an arm carried by said shaft between said drums for rotation with said shaft and projecting radially therefrom for swinging movement about an axis substantially normal to the axis of said shaft, said pawl and said hook being carried at the free end of said arm, said arm further having a portion projecting beyond said pawl and said hook to operatively engage said cam means.

4. The device of claim 3 in which said driving means comprises a driven rotary cam, a spring, and a push-rod engaged at one end by said rotary cam and held in such engagement by said spring, the other end of said push-rod being operatively connected to said supporting means.

5. The device of claim 3 in which said cam means comprises a body member, pivot means supporting one end of said body member for limited oscillation about said pivot means in a plane substantially parallel to said shaft but spaced therefrom, said body member supporting a pair of substantially parallel arms projecting away from said pivot means and spaced slightly apart in the direction of said shaft axis, said portion of said supporting means projecting into coactive relation with the adjacent edges of said arms, that one of said arms nearest said date drum having a portion remote from said pivot means turned toward said date drum, the end thereof being operatively engageable by said means incorporated in said first series of indexing means, and the other of said arms having a portion, farther from said pivot means than said portion of said one arm, turned toward said date drum, and means yieldably urging said body member to swing about said pivot means to move said end of said portion of said one arm into such operative engagement with said means incorporated in said first series of indexing means, said portion of said supporting means engaging said portion of said other arm, upon angular oscillation of said supporting means, to move said end of said portion of said one arm out of such operative engagement with said incorporated means.

6. The device of claim 5 including a finger carried by said body member adjacent said pivot means, an abutment member carried by said date drum, said finger being movable into the path of said abutment means when said portion of said supporting means engages said portion of said other arm of said member to rock said cam means about said pivot means, and means causing said date drum to rotate freely when said finger is so positioned in the path of said abutment member, said abutment member striking said finger to stop the free rotation of said drum at a predetermined position.

7. The device of claim 6 in which said means causing said date drum to rotate comprises a counterweight fixed to said date drum at a point spaced from said abutment means.

8. The device of claim 5 in which certain of the indexing means of said first series comprises tabs projecting from the end of said date drum toward said month drum, the end of that tab corresponding to the numeral 28 lying in a plane spaced from the plane of those indexing means corresponding to the numerals 1 to 27 toward the month drum, the end of that tab corresponding to the numeral 29 lying in a plane closer to said month drum than the last said tab end, the end of that tab corresponding to the numeral 30 lying in a plane still closer to said month drum, and the end of that tab corresponding to the numeral 31 lying in a plane still closer to the month drum than the other of said tabs, such tabs comprising those means incorporated in certain ones of said

first series of indexing means and operatively engageable by said cam means, that indexing means of said second series corresponding to a twenty-eight-day month lying in a plane spaced from said month drum toward said date drum, that indexing means of said second series 5 corresponding to a twenty-nine-day month lying in a plane spaced from said month drum toward said date drum, but farther from said date drum than the first said indexing means, those indexing means of said second series corresponding to thirty-day months lying in a plane spaced from said month drum toward said date drum, but farther from said date drum than the second said indexing means, and those indexing means corresponding to thirty-one-day months being spaced still farther from said date drum than the other of said indexing means. 15

9. The device of claim 8 in which the indexing means of said second series corresponding to twenty-eight and twenty-nine day months comprises a plate having four arms projecting therefrom at right angles to each other, three of said arms being of equal length and the other of said arms being of a shorter length, means carried by said month drum and mounting said plate for rotation about an axis lying in a chord of said month drum, each arm carrying a toe turned out of the plane of said plate in the direction opposite that of month drum rotation, 20 such toes being successively engageable by said hook, and a stationary cam mounted in the path of the currently extended arm to engage that arm as said plate is moved past said cam to rotate said plate through 90°.

10. The device of claim 8 in which said pawl is fixedly mounted to the free end of said arm and projects therefrom toward said first series of indexing means, and including means carried by said arm and supporting said hook thereon for movement toward and away from said pawl, and means resiliently engaging said hook to urge it toward its position farthest from said pawl.

11. The device of claim 10 in which the means carried by said arm comprises a pin carried by said arm, said hook being journaled thereon for rocking movement thereabout in a plane substantially parallel to the plane of said pawl, and stop means limiting the extent of such rocking movement, and said last-named means comprises a spring carried by said arm and engaging said hook to urge it toward its last-said position, said pin projecting beyond the plane of said hook to further constitute that portion of said supporting means projecting into operative engagement with said cam means.

12. The device of claim 1 including a third drum, means mounting said third drum in spaced relation to the first and second said drums for relative rotation about said common axis, said third drum comprising a day drum provided with the names of the calendar days spaced about the periphery thereof, said drum being provided with a series of angularly spaced ratchet teeth, a ratchet dog, means operatively connecting said dog to said driving means, said dog being engageable with said

10

teeth to rotate said day drum through a predetermined angle upon each cycle of said driving means, and brake means yieldably restraining such rotation of said day drum.

13. For use with an automatic calendar of the type comprising a date drum provided with a series of numerals from 1 to 31, a month drum provided with the names of the calendar months, and means supporting said drums for relative rotation about a common axis, the invention of means for actuating said date drum upon the passage of each day and said month drum upon the passage of each month, said date drum being provided with a series of indexing means, one for each of said numerals, and said month drum being provided with a series of indexing means, one for each of said month names, said actuating means being supported between said drums and comprising a drive member supported for angular rotation about the axis of said drum supporting means a pawl operatively connected to said drive member and urged laterally toward successive operative engagement with said date drum indexing means, a hook mounted to move with said pawl, and guide means for so laterally urging said pawl, means for so angularly rotating said drive member once in each twenty-four hours, and means incorporated in said date drum indexing means, corresponding to the numerals 28, 29, 30 and 31, and cooperating with said guide means to shift said pawl and said hook successively closer to said month drum, the elements of said month drum indexing series corresponding to thirty-one-day months being located substantially in a common plane for operative engagement by said hook in its position corresponding to the numeral 31 in said date drum, the elements of said month drum indexing series corresponding to thirty-day months 25 being located in a common plane closer to said date drum for operative engagement by said hook in its position corresponding to the numeral 30 in said date drum, the element of said month drum indexing series corresponding to a twenty-nine-day month being located in a plane still closer to said date drum for operative engagement by said hook in its position corresponding to the numeral 29 on said date drum, and the element of said month drum indexing series corresponding to a twenty-eight-day month being located in a plane still closer to said date drum for operative engagement by said hook in its position corresponding to the numeral 28 on said date drum.
